UNITED STATES PATENT OFFICE.

CHARLES C. PARKER, OF BALTIMORE, MARYLAND.

JAR-CLOSURE.

1,239,299.

Specification of Letters Patent. Patented Sept. 4, 1917.

Application filed February 11, 1916. Serial No. 77,556.

To all whom it may concern:

Be it known that I, CHARLES C. PARKER, a citizen of the United States of America, and resident of Baltimore, Maryland, have 5 invented certain Improvements in Jar-Closures, of which the following is a specification.

This invention relates to certain improvements in the jar-closure shown and described in Letters Patent No. 1,135,713 granted to me on the 13th day of April in the year 1915, to which reference should be made; and it consists principally in a hollow diametrically contractible plug or stopper of 15 peculiar construction, adapted to be forced into the throat of a jar, and provided with a cap which rests upon and extends over the exterior lip of the jar, as will hereinafter fully appear.

20 In the further description of the said invention which follows, reference is made to the accompanying drawing forming a part hereof, and in which:—

Figure 1 is a vertical central section of 25 the upper portion of a jar to which the improved closure is applied, and Fig. 2 a top view of the same. Fig. 3 is an underside view of Fig. 2, and Fig. 4 an enlarged sectional view of a part of Fig. 1. Fig. 5 illustrates a different application of the closure, and Fig. 6 an enlarged sectional view of a part of Fig. 5.

Referring now to Figs. 1 to 4 inclusive, of the drawing, 1 represents the head of a 35 jar, and 2 an annular seat within the throat 3 of the same.

The closure consists of an inverted cup-shaped plug, having a flat crown *a* and a skirt *b* which is provided with an upwardly 40 and outwardly extending flange *c* whereby a contractible circular edge is produced, adapted to fit closely against the inner surface of the throat of the jar; combined with a cap *d* which covers the exterior lip *e* of the jar. 45 These parts are secured together preferably by means of staples *f* and *g* as shown in the drawing.

To fully understand the advantage of a cup-shaped plug provided with an upturned 50 flange as described, over a flat disk, as a device to close the mouth or throat of a jar, and produce a practically liquid-tight joint, it must be borne in mind that a flat disk of pulp board or some similar material, has 55 only a slight diametric compressibility, and is therefore unfitted for use should the disk

be applied to a jar having a throat of less than the standard diametric size.

In the cup-shaped plug, its skirt *b* has a certain diametric compressibility independently of the crown *a* from which it depends; and when its edge is provided with the upturned flange *c* which is susceptible to diametric contraction independently of the skirt, the compressibility of the plug is increased, and to such an extent that it is adapted as a closure for jars the throats of which differ considerably in size, and a close or liquid-tight joint thereby produced.

While a stopper constructed as described 70 is well adapted for the purpose in view, I now find it desirable to increase the diametric flexibility of the upturned flange *c* without correspondingly increasing the flexibility of the skirt. To this end, I increase 75 the diameter of the circular flat blank from which the plug is formed, and provide the skirt *b* at its junction with the upturned flange *c* with a crimp or annular open crease *h*, which is slightly closed as the plug is 80 forced into a jar.

The construction just described enables me to dispense with the reinforce shown and described in the said patent, which not only simplifies the device, but reduces the amount 85 of stock used in its production, and in consequence its cost.

In the present invention I provide the cap *d* with a lifting tongue *i* similar to the one shown in the said patent, which was 90 intended to stand slightly above the upper surface of the cap to admit of the insertion of the thumb nail underneath it for unsealing purposes. In practice however, the insertion of the nail was not easily accomplished; and in order to effect a well defined elevation of the tongue I form on the crown *a* of the plug, and underneath the tongue, a slight bulge *j* which serves to lift the tongue and retain it in an elevated condition as shown.

In Fig. 5 the edge of the cap *d* is shown as inserted in a groove *j* formed in the lip of a jar or tumbler adapted to hold heated materials such as jelly; and in order that 105 the jar will be hermetically sealed, I form on the peripheral edge of the cap, after the paraffining operation which renders it water proof, an annular bead *k* of paraffin which upon coming into contact with the 110 heated glass, flows and fills the groove and becomes hard as the vessel cools.

I claim as my invention:—

1. A jar closure which consists of an inverted cup-shaped plug or stopper having the skirt thereof provided with an outwardly and upwardly extending continuous or unbroken creased flange which produces a contractible circular edge adapted to come in contact with the inner surface of the throat of the jar, combined with a cap adapted to 10 cover the exterior lip of the jar, and to which the stopper is secured, a raisable tongue on the cap and a bulge formed on the crown of the plug upon which the tongue rests, substantially as specified.

2. A jar closure comprising an inverted 15 cup-shaped plug or stopper having the skirt thereof provided with an outwardly and upwardly extending creased flange, adapted for insertion in the throat of the jar, combined with a cap adapted to cover the exterior lip of the jar, the edge having an annular bead which is liquefiable by heat, substantially as and for the purpose specified.

CHARLES C. PARKER.
